ASSIGNORS TO WHITING FOUNDRY EQUIPMENT COMPANY, OF HARVEY, ILLINOIS,
A CORPORATION OF ILLINOIS.

LADLE-TURNING MECHANISM.

1,323,137.

Specification of Letters Patent. Patented Nov. 25, 1919.

Application filed April 25, 1919. Serial No. 292,590.

To all whom it may concern:

Be it known that we, BRADFORD H. WHITING, residing at Chicago, in the county of Cook and State of Illinois, and JOHN S. TOWNSEND, residing at Harvey, in the county of Cook and State of Illinois, both citizens of the United States of America, have invented a certain new and useful Improvement in Ladle-Turning Mechanism, of which 10 the following is a specification.

This invention relates to mechanism for turning ladles used in foundries, furnaces and the like, containing more or less large bodies of molten metal, wherein, because of 15 the danger of spilling the molten metal, very positive powerful machinery is required, and wherein, because of the great and variable heat created by the molten metal there is great danger of irregular expansion in 20 various parts of the machinery, with consequent danger of faulty operation.

The object of the invention is to provide a mechanism for turning a ladle and to so mount it that these difficulties are reduced to 25 a minimum, if not entirely eliminated.

The invention consists in mechanism for carrying out the foregoing objects, which can be easily and conveniently made, which is satisfactory in operation, and is not readily liable to get out of order. More in detail, the invention consists in making a ladle turning mechanism which is mounted bodily on the ladle trunnion and which, if expandible at all, expands with reference to the 35 trunnion only, giving this ladle turning mechanism a flexible foot or anchor hold on another relatively stationary part of the device so that turning of the ladle can be effected. The invention further consists in 40 the many features and details of construction hereafter more fully set forth in the specification and claims.

Referring to the drawings, in which like numerals indicate the same parts throughout 45 the several views,

Figure 1 is a plan view of a ladle turning mechanism illustrating this invention in its preferred form.

Fig. 2 is a side view of the mechanism of 50 Fig. 1, part of the case being broken away to show the internal operating mechanism.

Fig. 3 is a sectional end view taken on the line 3-3 of Fig. 2.

Like all devices of the type referred to, the metal carrying ladle 10, is provided on opposite sides with horizontally extending trunnions 12, only one being shown in the drawings, and each trunnion is journaled in the lower extremity of an upwardly U-shaped bail 14 attached to a traveling 55 crane or other suitable lifting and transporting mechanism. For the purposes of the present invention, the bail 14 is a stationary member within which the trunnions 12 turn to rotate the ladle 10. 60 65

The present rotating mechanism comprises a worm wheel 16, rigidly secured upon trunnions 12, by any suitable means, as for instance a key 18. In the face of this worm wheel 16 meshes a worm 20, 70 mounted on a shaft 22, journaled in a case casting 24, preferably reinforced and stiffened by arms 26 and 28, and supported by the hub 30, journaled on the hub 16^a of worm wheel 16, heretofore referred to. Oiling of 75 this shaft is effected by removing the plugs 29. The shaft 22 also carries a spiral gear 32 which meshes with a worm 34 on a shaft 36, driven by operating handle 38. This shaft 36 is, as shown, carried by arm 28. The 80 lower part of the mechanism just described is inclosed by a depending case member 40, detachably secured in position by bolts or screws 42 and 44, entering the casting 24 or a part thereof, from which it follows that all 85 of the operating parts just described, are carried by the hub 30, journaled on hub 16^a of gear 16. This case is accessible through its end via the cover plate 43 detachably secured in place by the screws 45. 90 95

It is, of course, obvious that in order to effect rotation of ladle 10 by turning handle 38 and consequently the intervening gear mechanism, it is necessary that the mechanism thus far described be at least loosely anchored to something stationary. This is accomplished by providing upon the top of the case 24 a pair of parallel lugs 48 and 50 forming a U-shaped recess 52 between them within which the bail 14 lies 100 and is adapted to move or less freely move. In the particular construction shown, the bail is reinforced and protected at this point by a U-shaped plate 54 held in place by a screw 56. The fit of the bail in this 105 U-shaped recess 52 is sufficiently loose so

that no amount of expansion, contraction, or warping of the bail 14, due to the heat of the metal in ladle 10 will have any effect in distorting any of the operating mechanism.

In the operation of the device, the operator turns handle 38 in one direction or the other, as the case may be, thus rotating worm 34 to successively drive spiral gear 32, shaft 22, worm 20, worm wheel 16 and finally trunnion 12 and ladle 10, arm 48 or 50, as the case may be, bearing against plate 54 of bail 14 to permit this turning action but without being in any way tied to the bail which is free to contract and expand as much as it pleases. The bail is especially subject to such contraction and expansion due to the fact that the heat of the molten metal in the ladle 10 passes up above and over the sides of the ladle more easily than in any other direction and thus strikes, heats and expands those portions of the bail which are above the upper edge thereof, the same not being shown in the drawing. The heat is transmitted from these parts above the ladle to the parts shown in the drawings, immediately adjacent to the operating mechanism.

The construction of this invention is especially valuable in view of the fact that a worm or spiral gear mechanism is more easily distorted and rendered inefficient if not inoperative by slight changes in alignment of the various parts, and in view of the fact that the laws of some States, notably the State of Pennsylvania, prohibit the use of any other than worm or spiral gear operating mechanism in connection with molten metal ladles, this because of the well known fact that this form of gearing acts within reasonable limits as an automatic brake; *i. e.*, the load cannot run away with it, as is possible where ordinary spur gearing is used.

The use of spiral gearing is especially valuable because, by its use, the power ratio can be varied from 1 to 33 or 1 to 127 by simply changing the size of the spiral gearing without changing the centers. This is very important in cases where a ladle happens to work hard and more leverage is needed, or where it is desired to turn the ladle slower in order to get a finer adjustment in pouring, or, conversely, where it is desired to speed up the pouring.

Having thus described our invention what we claim as new and desire to secure by Letters Patent, is:—

1. In mechanism of the class described, in combination with a ladle and a supporting mechanism therefor in which it is journaled, ladle turning machinery mounted and carried by the journal mechanism of the ladle, and a loose anchor between said machinery

and the ladle supporting mechanism, permitting free expansion of the supporting mechanism, for the purposes set forth.

2. In mechanism of the class described, a ladle and its trunnion, a bail in which said trunnion is journaled, gear mechanism rigidly attached to and operating the trunnion and solely supported thereby, except for a loosely fitting anchor which engages the bail, while permitting free expansion and contraction of the bail, for the purposes set forth.

3. In mechanism of the class described, the combination of a ladle, a trunnion extending therefrom, a suspending bail in which said trunnion is journaled, a case mechanism also journaled on the axis of the trunnion, an anchor on the case loosely embracing the bail without interfering with its expansion and contraction, and gear mechanism contained within the case operatively connected to and supported by the trunnion, for the purposes set forth.

4. In mechanism of the class described, a ladle, a trunnion extending therefrom, a bail carrying the trunnion in rotative relation therewith, a worm wheel rigid on the trunnion, a hand operated mechanism for driving said worm wheel, a case journaled on said worm wheel and inclosing the mechanism for driving the worm wheel, and an anchor from the case to the bail loosely engaging the bail to permit the latter free expansion and contraction, for the purposes set forth.

5. In mechanism of the class described, the combination with a ladle, a bail therefor, a trunnion on the ladle journaled in the bail, a worm gear rigid on the trunnion, a case inclosing the worm gear journaled on and carried by the worm wheel, an anchor on the case loosely connected to the bail, other gearing within the case journaled therein and meshing with the worm wheel, and means extending outside the case adapted for manipulating said other gearing, for the purposes set forth.

6. In mechanism of the class described, a ladle, a trunnion therefor, a supporting member carrying the trunnion, a worm wheel rigid on the trunnion, a shaft carrying a worm meshing in said worm wheel, a case provided with bearings for said shaft, means supporting said case from the trunnion, an anchor from the case to the trunnion support, permitting free expansion of the trunnion support, and mechanism for rotating said shaft, for the purposes set forth.

7. In mechanism of the class described, the combination with a trunnion to be rotated, a bail carrying the trunnion, a worm wheel upon the trunnion, a case inclosing the worm wheel and journaled about the axis of the trunnion, a worm meshing with said

worm wheel, a shaft for the worm journaled within said case, a spiral gear on said shaft, a second worm meshing with said spiral gear, a shaft for said second worm, journaled in the case, a hand operated member for said last mentioned shaft, an anchor from the case to the bail, loosely engaging the same to permit expansion thereof, all

of the parts being shaped, arranged and disposed as shown and described, for the purposes set forth. 10

In witness whereof we have hereunto subscribed our names.

BRADFORD H. WHITING.
JOHN S. TOWNSEND.
